(57) **CLAIM**

The ornamental design for a clip for portable communications device, substantially as shown and described.

DESCRIPTION

FIG. 1 is an elevated right, front perspective view of the clip for portable communications device;

FIG. 2 is a top view of the clip for portable communications device;

FIG. 3 is a side view of the clip for portable communications device;

FIG. 4 is a rear view of the clip for portable communications device; and,

FIG. 5 is an elevated right, front perspective view of the clip for portable communications device according to another embodiment, shown as having holes for a neck strap (shown in broken lines) and attached to a portable communications device (shown in broken lines).

All aspects of the second embodiment are the same as the first embodiment with the exception of the holes for the neck strap.

The broken lines in FIG. 5 are for illustrative purposes only and form no part of the claimed design.
